UNITED STATES PATENT OFFICE

FRANK E. NEWTON, OF HARTFORD, CONNECTICUT

MACHINE FOR SHAVING AND SLOTTING SCREWS

Application filed December 18, 1931. Serial No. 581,827.

This invention relates to a machine for shaving and slotting wood screws of the type in which the blanks are automatically fed to chucks on rotatory spindles mounted in a rotatory head that carries the spindles from station to station and dwells in positions to allow a shaving tool, slotting saw and re-shaving tool to operate upon the blanks.

10 The object of the present invention is to so relate the movements of the head, and the positions and actions of the cutting tools, that there will be a reduction in the distance of the head movements and in the 15 time of the head dwells, with the result that the speed of operation may be increased with a saving of power, decrease in wear of the elements, and more perfect product rapidly produced than with the present machines of this type.

In the prior wood screw shaving and slotting machines in general use, on which the present conception is an improvement, the spindle carrying heads are given intermittent movements of 180°. At the first station the blanks are loaded into the chucks and shaved, and after being slotted at the second station are re-shaved and discharged at the first station; that is, there are two 30 movements of the head for each cycle, and the dwell at each of the two stations is determined by the time it takes to load, shave, re-shave and discharge at the first station.

35 By means of the instant improvement the head is given movements of 120°, that is, three intermittent movements for each cycle. The blanks are loaded at the first station, shaved at the second station, sawed at the third station, and re-shaved and discharged at the first station. This is readily accomplished as the shaving operation takes longer time than it takes to saw the slot, or to load, re-shave and unload, therefore the 40 operations are more quickly accomplished and the output of the machine greatly increased.

In the accompanying drawings Fig. 1 is a 50 plan view of so much of a wood screw shaving and slotting machine as is necessary to

an understanding of the present invention. Fig. 2 is a vertical section taken on approximately the plane indicated by the dotted line 2-2 on Fig. 1, illustrating the relative positions of the feed and the operating tools. Fig. 3 is an elevation of the mechanism for imparting three intermittent rotatory movements to the spindle carrying head during each cycle of action. Fig. 4 is an elevation looking toward the spindle head from the plane indicated by the dotted line 4-4 on Fig. 1, showing the spindle rotating means. Fig. 5 is a horizontal section on the plane indicated by the dotted line 5-5 on Fig. 2, showing the slotting saw about to engage a screw blank held by a spindle chuck. Fig. 6 is a horizontal section on approximately the dotted line 6-6 on Fig. 5. Fig. 7 is a vertical section on plane indicated by dotted line 7-7 on Fig. 5. Fig. 8 is a detail view of part of the blank back rest mechanism. Fig. 9 shows a side elevation of the arms which carry the back rest oscillating cams. Fig. 10 shows a side elevation of the back rest carrying arms. Fig. 11 shows a plan of the means for drawing the blanks into engagement with the slotting saw. Fig. 12 shows a plan of the means for clamping the withdrawing elements upon the blanks.

The spindle head of the machine illustrated is comprised of a pair of triple arm spiders 1 which extend from a sleeve 2 that is fastened to a shaft 3 which is rotatably mounted in bearings in the frame members 4.

5 Fastened to the shaft 3 are a drive disk 5 and an index disk 6. Turning loosely on the shaft is a toothed segment 7 which carries a pawl 8 that is designed to engage shoulders 9, which are 120° apart on the periphery of the drive disk 5. Meshing with the segment 7 is a gear 10 which is engaged by a toothed segment 11 on a lever 12 that is pivoted on a shaft 13. The lever 12 has a projecting boss 14 that rides on the cam 15 on the periphery of the disk 16 which is fastened to the cam shaft 17.

The cam shaft is driven by gear 18 from pinion 19 on the drive shaft 20. Each rotation of the cam 15, through the medium of 100

the lever and intermeshing gear and segments, causes the pawl 8 to turn the shaft which carries the spindle head, 120°, Figs. 1, 3.

- 5 Adapted to engage notches 21, which are 120° apart in the periphery of the index disk 6, is a tooth 22 on the end of a lever 23 which is pivoted on a stud 24. A spring 25 connected to the outer end of this lever tends 10 to hold the tooth in engagement with the periphery of the index disk. The inner end of the lever 23 has a shoe 26 that is adapted to be engaged by a cam block 27 which is adjustably fastened to the disk 16, Fig. 3. 15 This cam block at the proper intervals engages the lever 23 and withdraws the tooth from a notch in the periphery of the index disk so that the pawl may rotate the drive disk and shaft. At the end of the push of 20 the pawl the spring draws the lever so that the tooth will drop into a notch and stop the rotation of the shaft with the spindles in exact position with relation to the tools.

This mechanism produces a very rapid rotation of the shaft and consequently gives the spindles a quick revolving movement, and previously it frequently happened that, owing to the speed and momentum of the parts, the index tooth would not enter the 25 notch of the index disk and the shaft would turn too far, and thus derange the timing relations of the mechanisms.

To obviate this and ensure the entry of the tooth into an index notch of the disk, 30 without applying excessive resistance to control these movements, the female member 28 of a split ring clutch is mounted so as to rotate with the shaft 3, while the male member 29 of the clutch is held from rotation 35 by an arm 30 which is fastened to the shaft 13, Fig. 3. As the segment nears the end of its upward movement this clutch is set by a stem 31 that is attached to the female member and is engaged and lifted by an arm 40 32 adjustably fastened to the segment lever 12. A spring 33 pulls the stem down. This causes the clutch to retard the rotation of the shaft as it approaches the completion 45 of its rotary movements, Fig. 3.

50 There is a spindle 34 rotatably mounted in each of the three arms of the spindle head. Each spindle has a hollow head 35 on which a pulley 36 is fastened. In each spindle head are chuck jaws 37 carried by 55 levers 38 that are engaged by levers 39. The levers 39 have inclined tails 40 which when engaged by the collar 41 slidable on the head, cause the levers to close the chuck jaws on a blank. When the collar is slid 60 forward and the jaws allowed to open, a spring pressed pin 42 ejects the blank from the chuck jaws, Fig. 5. The collar 41 is slid back and forth on the spindle by the arm 43 that is moved along the bar 44 by 65 the cam 45 on the cam shaft 17, Fig. 4.

These elements are adjusted so that the chuck jaws are opened to receive blanks and closed to clamp the blanks while the spindles are in re-shaving position, which position is indicated by X on Fig. 2. After the blanks have been carried to shaving position, indicated by Y on Fig. 2, then to slotting position indicated by Z on Fig. 2, and finally back to re-shaving position, the jaws are opened after the re-shaving has been accomplished so that the blanks may be ejected.

The blanks are brought down into the chuck jaws by any common feed mechanism, for example, by the fingers 46 mounted on the end of an oscillatory arm 47, Fig. 2. A belt 48 running around pulleys 49 and 50 is guided so as to engage the pulleys 36 on the spindles which are in shaving and re-shaving positions, but be out of engagement with the pulley on the spindle that is in slotting position, Fig. 4. The pulley 50 is fastened to the shaft 51 that has a pinion 52 engaged by a gear 53 on the shaft 20, Figs. 3, 4. As a spindle moves into slotting position its pulley 36 is engaged by a friction brake 54 which ensures the stopping of its rotation while the blank is being slotted, Fig. 4.

After a blank has been passed into and is clamped by the chuck jaws the spindle head is rotated 120° and stopped while the blank is shaved by the tool 55. When the shaving is completed the head is rotated another 120° and dwells while a slot is being cut by the saw 56. Upon the completion of the slotting, the head is rotated 120° back to first position where it dwells while the blank is re-shaved by the tool 57. After re-shaving the chuck jaws are opened and the blank ejected and another blank entered. As previously mentioned, shaving requires more time than is required for the slotting, or for re-shaving and loading and ejecting. Therefore the dwells in the rotary movements of the spindle head are controlled by the time it takes for shaving.

The re-shaving tool 57 is clamped to a slide 58 which is movable in and out on a way 59, being drawn outward by a spring 60, Figs. 1, 2. This slide is moved inward at the proper time by a cam 61 on the cam shaft 17 acting on the lower end of the lever 62 that is fulcrumed on the shaft 63. This lever at its upper end has an adjusting screw 64 which engages a lug 65 projecting from the slide 58, Fig. 2.

The shaving tool 55 is clamped to a slide 66 that is moved in and out on the way 67. It is drawn outward by a spring 68 and moved inward by a cam 69 on the shaft 17 acting on the lever 70 that is fulcrumed on the shaft 63. This lever has a downwardly extending arm 71 that is connected with the adjusting screw 72 which engages the lug 74 projecting from the slide 66, Fig. 2.

While the re-shaving took 57 is cutting the blank is sustained by a back rest 75 carried by a head 76 on an arm 77 that is attached by a pivot 78 to a bracket 79 which is fastened to a member of the frame. While the shaving tool 55 is cutting the blank is sustained by a back rest 80 carried by a head 81 on the arm 82 that is attached by a pivot 83 to a bracket 84 fastened to the frame, Figs. 8, 10.

Movable along the shaft 3 is a semi-circular casting 85, Figs. 8, 9. One end of a rod 86 is connected with a lug 87 extending from this casting and the other end of this rod is adjustably connected with the upper end of an arm 88, Fig. 5. The lower end of the arm 88 is fastened to a bar 89 that is slidably mounted in the frame and is reciprocated at the proper times by a cam 90 on the cam shaft 17, Fig. 6. By this means the casting 85 is moved back and forth along the shaft 3. On an arm 91 extending from the casting is a wedge cam 92 that is designed to engage the head 76 and turn inward the arm 77 which carries the rest 75 that backs the blank in re-shaving position, Figs. 2, 7, 8. Extending from the casting 85 is a wedge cam 93 that is designed to engage the head 81 and turn inward the arm 82 which carries the rest 80 that backs the blank in shaving position, Figs. 2, 7, 8. As the re-shaving cut requires less time than the shaving cut the cam 92 is much shorter than the cam 93. Springs 94 hold the rest heads out against these cams.

at 106 to an arm 107 fastened to the upper end of a vertical shaft 108, Figs. 5, 11. Fastened to the lower end of the vertical shaft 108 is an arm 109 that has a shoe 110, Figs. 5, 11. A link 111 connects this shaft with a lever 112 that is pivoted at 113 and is engaged by a cam 114 on the shaft 17, Figs. 7, 11. The cam 114 through the connections recited causes the jaws 104 at the proper times to pull the blank forward into engagement with the slotting saw. A spring 115 connected with the lever 107 causes the jaws to move backward.

One of the jaws 104 is closed against the blank by the engagement of the inclined edge 116 of the arm 105 with the inclined face of the fixed arm 117 as the arms are drawn forward, Fig. 12. The edge of the other arm 105 is connected by a link 118 with the upper end of an arm 119 on the shaft 120 to which is fastened an arm 121, Figs. 7, 12. A rod 122 engaged by one limb of an angle lever 123 is yieldingly connected with the lower end of the arm 121 by a spring 124. The lever 123 is engaged by a cam 125 on the shaft 17, Fig. 7. By this means the jaw 104 on the outer arm 105 is closed against the blank. The other limb of the angle lever 123 is connected by a link 126 with a projection from the arm 121, Fig. 7. By these latter connections the outer jaw is released.

In the machine described the chuck jaws in upper position are opened and after receiving a blank are closed.

The slotting saw 56 is detachably fastened to the upper end of a vertical shaft 95. On the lower end of this shaft is a bevel gear 96 and pawl mechanism, being slowed down that is engaged by a bevel pinion 97 on the 40 horizontal shaft 51, Fig. 6.

The spindles are capable of a short movement longitudinally in their bearings in the spindle head. The amount of this movement is indicated by the space 98 between the 45 shoulders 99 on the spindle and the head frame, Fig. 1. Leaf springs 100 fastened to the arms of the head and engaging groove collars 101 on the spindles tend to draw the spindles out and close this space. When the 50 spindles are in re-shaving position and also in shaving position, the heads of studs 102 threaded into the ends of the spindles engage with the face of a fixed arc-shaped abutment 103, Figs. 1, 4, and the spindles 55 pushed slightly inward and retained in the proper positions for the actions of the re-shaving and shaving tools on the blanks.

The spindle head is then given a quick rotatory movement of 120° by the ratchet near the end of the movement by the brake 105 and indexed with the blank in shaving position. After the shaving tool has been moved up and completed its cut and moved away the spindle head is given another quick movement of 120° , being braked and indexed as before when the blank is in slotting position. The pulling jaws are then closed upon the blank and the blank drawn forward into engagement with the saw. After the slot is cut the pulling jaws are 110 opened and the head is given a third movement of 120° carrying the blank to starting position. When this position is reached the blank is re-shaved and then the chuck jaws are opened to permit the ejection of the finished blank and allow the insertion of another blank in the same chuck jaws. While one blank is being shaved the preceding 115 120

In sawing position the spindles are not backed by the abutment, but are drawn forward against the tension of the springs 100 by means of jaws 104 that close upon and grip the blanks under the heads, Figs. 5, 11, 12, and pull the blanks against the teeth of the slotting saw. These jaws are carried by the ends of curved arms 105 that are pivoted 60 65 125 130

ing the spindles at each of the stations is short. Owing to these conditions a large output of accurately finished articles is produced in a much shorter time than was possible with the prior machines of this type.

The invention claimed is:

5 during each complete rotation of said head, three spindles rotatably mounted one hundred and twenty degrees apart in said head, means for rotating said spindles at the first and second stops and interrupting the rotation of the spindles at the third stop of said head, blank holding chuck jaws carried by said spindles, means for opening and closing said chuck jaws at the first stop of said head, a re-shaving tool movable toward the axis of the chuck jaws at the first stop, a shaving tool movable toward the axis of the chuck jaws at the second stop, blank backing means movable toward the axis of the chuck jaws at the first and second stops, a rotatable slotting saw adjacent the third stop, and means for drawing the spindles axially toward the slotting saw at said third stop said stops of the head carrying the spindles being only as long as the shaving tool operates on the blanks.

7. A shaving and slotting machine comprising a rotatable head, mechanism for imparting three intermittent rotary movements during each complete rotation of said head, three spindles rotatably mounted in said head, means for rotating said spindles at the first and second stops and interrupting the rotation of the spindles at the third stop of said head, blank holding chuck jaws carried by said spindles, means for opening and closing said chuck jaws at the first stop of said head, shaving tools movable toward the axis of the chuck jaws at the first and second stops, a rotatable slotting saw adjacent the third stop, and means for drawing the spindles axially toward the slotting saw at said third stop, said stops of the head carrying the spindles being only as long as the shaving tool operates on the blanks.

8. A shaving and slotting machine comprising a rotatable head, mechanism for imparting three intermittent rotary movements and stopping said movements at three stations during each complete rotation of said head, three spindles rotatably mounted in said head, means causing the rotation of said spindles at the first and second stations and interrupting the rotation of the spindles at the third station, blank holding chuck jaws carried by said spindles, means for opening and closing said chuck jaws at the first station, a re-shaving tool movable toward the axis of the chuck jaws at the first station, a shaving tool movable toward the axis of the chuck jaws at the second station, a rotatable slotting saw adjacent the third station, and means for drawing the spindles axially toward the slotting saw, said stops of the head carrying the spindles being only as long as the shaving tool operates on the blanks.

9. A shaving and slotting machine comprising a rotatable head, mechanism for imparting three intermittent rotary movements

of one hundred and twenty degrees each to said head, three spindles rotatably mounted one hundred and twenty degrees apart in said head, means for rotating said spindles at the first and second stops and interrupting the rotation of the spindles at the third stop of said head, blank holding chucks carried by said spindles, means for opening and closing said chucks at the first stop of said head, a re-shaving tool movable toward the axis of the chucks at the first stop, a shaving tool movable toward the axis of the chucks at the second stop, a rotatable slotting saw adjacent the third stop, and means for drawing the spindles axially toward the slotting saw at said third stop said stops of the head carrying the spindles being only as long as the shaving tool operates on the blanks.

10. A shaving and slotting machine comprising a rotatable head, mechanism for imparting three intermittent rotary movements with a dwell between each movement during each complete rotation of said head, three spindles rotatably mounted one hundred and twenty degrees apart in said head, means for rotating said spindles during the first and second dwells and interrupting the rotation of the spindles during the third dwell of said head, blank holding chucks carried by said spindles, means for opening and closing said chucks during the first dwell of said head, a shaving tool movable toward the axis of the chucks during the first dwell, a shaving tool movable toward the axis of the chucks during the second dwell, a rotatable slotting saw located adjacent the spindles at the third dwelling position, and means for drawing the spindles axially toward the slotting saw during the third dwell of the head, said dwells of the head carrying the spindles being only as long as the shaving tool operates on the blanks.
